US00D960120S

(12) **United States Design Patent** (10) **Patent No.:** **US D960,120 S**
Cao et al. (45) **Date of Patent:** **** Aug. 9, 2022**

(54) **MOBILE PHONE**

(71) Applicant: **HUAWEI TECHNOLOGIES CO., LTD.**, Shenzhen (CN)

(72) Inventors: **Guang Cao**, Shanghai (CN); **Ye Rang Lee**, Shenzhen (CN); **Lu Huang**, Paris (FR); **Sylvain Gerber**, Paris (FR); **Zhiqiang Jiang**, Shanghai (CN)

(73) Assignee: **HUAWEI TECHNOLOGIES CO., LTD.**, Shenzhen (CN)

(**) Term: **15 Years**

(21) Appl. No.: **29/726,136**

(22) Filed: **Feb. 28, 2020**

(30) **Foreign Application Priority Data**

Aug. 30, 2019 (CN) 201930477727.2
